UNITED STATES PATENT OFFICE.

CARL W. RIIHIKOSKI, OF PORTLAND, OREGON.

TOILET-SEAT.

1,217,506.

Specification of Letters Patent. Patented Feb. 27, 1917.

Application filed September 15, 1916. Serial No. 120,288.

To all whom it may concern:

Be it known that I, CARL W. RIIHIKOSKI, a subject of Finland, Russia, residing at 905 Patton avenue, Portland, in the county 5 of Multnomah, State of Oregon, have invented certain new and useful Improvements in Toilet-Seats, of which the following is a description, reference being had to the accompanying drawings, forming a part 10 hereof.

The object of the invention is to provide a simple and comparatively inexpensive and readily attachable auxiliary toilet seat adapted for children's use and having means 15 for engagement with a bowl of any of the ordinary commercial constructions whereby accidental displacement is prevented.

Further objects and advantages of the invention will appear in the following description of a preferred embodiment, it being understood that changes in the form, proportion and minor details may be resorted to within the scope of the appended 20 claims without departing from the spirit of 25 the invention.

In the drawing.

Figure 1 is a perspective view of the attachment arranged in the operative position on a bowl.

30 Fig. 2 is a sectional view of the same showing the bowl in dotted lines to indicate clearly the means whereby the platform is secured against displacement.

Fig. 3 is a perspective view of the attachment when folded for storage or transportation.

Fig. 4 is a detail view in perspective of a portion of the platform to illustrate the means for engagement with a cover hinge 40 rod at the rear of the platform.

The essential features of the illustrated embodiment of the invention consist of a platform 10 provided with a suitable guard 11 forming a back and arms which may be 45 connected at the front by a strap or other flexible means 12, a rear platform anchoring means consisting of hooked members 13 adapted for engagement under and in rear of the ordinary cover hinge rod 14, the en- 50 gagement of said members with the hinge rod being effected by raising the forward end of the platform and with the rear rocker edge 15 thereof resting on the flange of the bowl, sliding same rearwardly to the proper 55 position and then depressing the forward

edge of the platform, and a front platform anchoring means consisting of a detent 16 adapted for engagement under the bowl rim 17 at the front, a foot rest 18 being suspended from the detent and provided with bearing fingers 19 to engage the under surface of the platform for the purpose of locking the detent in place and steadyng the entire structure. 60

In the construction illustrated, the detent 65 comprises a part of a swinging frame of which the arms 20 are pivotally mounted, as at 21, upon the platform near the sides thereof and the suspending rod 22 of the foot rest are fulcrumed upon said frame at either side 70 of the bowl engaging portion of the detent and are extended to form the bearing fingers 19 which preferably come in contact with a wear plate 23 secured to the platform and the detent is preferably provided with a 75 tubular cushioning means 24 to avoid mar- ring the rim of the bowl. Also a cushioned contact 25 may be provided at the rear of the foot rest to bear against the surface of 80 the bowl.

It will be understood that in placing the attachment after the engagement of the rear holding means with the hinge rod 14, the swinging detent should be moved forward and downward from the folded position indicated in Fig. 3 in order to pass under the bowl rim, and thereupon the rearward swinging movement of the foot rest, bringing the bearing fingers 19 into contact with the under surface of the platform and 85 the rear of said foot rest into contact with the bowl, will lock the parts to prevent accidental displacement or vibration, whereas it is only necessary to draw the foot rest forward sufficiently to disengage the bearing 90 fingers from the under surface of the plat- form to enable the operator to fold the foot rest within the detent frame and dispose the parts as indicated in Fig. 3 with the mov- 95 able elements housed within the guard on top of the upper side of the platform. With the parts in this position, the attachment 100 can be readily stored or packed for ship- 105 ment.

What I claim is:—

1. An auxiliary bowl engaging toilet seat, having a platform provided with rear means for engaging under and in rear of an element mounted on the bowl, a movable bowl rim engaging element to lock the front end 110

of the platform against elevation, and a foot rest for holding the rim-engaging element in operative position.

2. An auxiliary bowl engaging toilet seat, 5 having a platform provided at its rear with an upturned hooked element for engaging a bowl cover hinge, a movable bowl rim-engaging element to lock the front end of the platform against elevation, and a foot rest for holding the rim-engaging element in operative position.

3. An auxiliary bowl engaging toilet seat, 15 having a platform provided with rear means for engaging under and in rear of an element mounted on the bowl, a movable bowl rim-engaging element to lock the front end of the platform against elevation and consisting of a swinging frame having a detent for disposition under a bowl rim, and a foot 20 rest suspended from said frame.

4. An auxiliary bowl engaging toilet seat, 25 having a platform provided with rear means for engaging under and in rear of an element mounted on the bowl, a movable bowl rim-engaging element to lock the front end of the platform against elevation, and consisting of a swinging detent for engagement under a bowl rim, and a foot rest suspended from said detent.

5. An auxiliary bowl engaging toilet seat, 30 having a platform provided with rear means for engaging under and in rear of an element mounted on the bowl, a movable bowl rim-engaging element to lock the front end of the platform against elevation, and consisting of a swinging detent for engagement under a bowl rim, and a foot rest suspended from said detent, and having bearing fingers 35 for engagement with the under surface of the platform.

6. An auxiliary bowl engaging toilet seat, 40 having a platform provided with rear means for engaging under and in rear of an element mounted on the bowl, a movable bowl rim-engaging element to lock the front end 45 of the platform against elevation, and consisting of a swinging detent for engagement under a bowl rim, and a foot rest suspended from said detent, and provided with side suspension rods terminally extended to form 50 rearwardly projected bearing fingers.

This specification signed and witnessed this 9th (ninth) day of September A. D. 1916.

CARL W. RIIHIKOSKI.
